UNITED STATES PATENT OFFICE.

THOMAS M. SNELLING, OF LA JARA, COLORADO.

WIRE-STRETCHER.

1,147,655.

Specification of Letters Patent. Patented July 20, 1915.

Application filed January 2, 1914. Serial No. 809,943.

To all whom it may concern:

Be it known that I, THOMAS M. SNELLING, a citizen of the United States, residing at La Jara, in the county of Conejos and State 5 of Colorado, have invented certain new and useful Improvements in Wire-Stretchers; and I do hereby declare the following to be a full, clear, and exact description of the invention, such as will enable others skilled 10 in the art to which it appertains to make and use the same.

This invention relates to wire stretchers, and one of the principal objects of the same is to provide an efficient tool of simple construction for stretching the wires between two fence posts, after the wires have been severed, so the ends may be connected or spliced together to take up the slack and to tighten the wires.

Another object of the invention is to provide means for clamping the wire at two points after the line wire has been severed and for drawing the severed ends together a sufficient distance so that they can be 20 united by pliers or other tools for taking up the slack in the line wires, such stretcher being so constructed that a free space is given for the splicing operation.

These and other objects may be attained 30 by means of the construction illustrated in the accompanying drawing, in which—

Figure 1 is a perspective view of a wire stretcher secured to the upper line wire of a fence, said line wire being severed and the 35 wire stretcher being in position to pull the wire from opposite directions at opposite sides of the parted ends, Fig. 2 is a sectional view on a larger scale of the rack and pawl mechanism in one of its positions, Fig. 3 is 40 a side elevation of the same in another position, Fig. 4 is a detail sectional view and partial elevation of one of the wire clamps, Fig. 5 is a side elevation of the same, and Fig. 6 is a sectional view taken on the line 45 6—6 of Fig. 3, looking in the direction indicated by the arrow.

Referring to the drawings, the numeral 1 designates one member of the stretcher and 2 is the other member thereof. The 50 member 1 has an angular arm 3 and the member 2 has a similar arm 4. These arms each have a terminal lug 5—6.

The wire clamps are substantially identical in construction, and hence the description of one will serve for both. Each clamp 55 consists of a lever 7 having an eccentric

head 8 provided with biting teeth to engage the line wire, and said lever is pivoted upon a bolt 9 extending eccentrically through the head 8 and inserted into the arm 4, as shown 60 in Fig. 4. The head 4 is disposed immediately under the lug 6, and the latter serves as the stationary jaw of the clamp. Formed integral with the lever 7 is a guard 10, and when the lever 7 is swung in one direction, 65 the wire *a* may be inserted between the lug 6 and the head 8 of the clamp, and when the lever is swung in the opposite direction, the wire is clamped between the lug 6 and the head 8. 70

The member 1 of the stretcher is provided with spaced guides 11—12 connected thereto by rivets or bolts 13, and the member 2 is mounted to slide in said guides. The member 2 on its lower edge is provided with a 75 series of ratchet teeth 14. A lever comprising spaced members 15 is pivotally connected at 16 to depending bearing members 17 rigidly connected to the member 1 by rivets or bolts 18. Pivoted at 19 between the 80 members 15, is a pawl 20 which is curved upwardly at one end to engage the teeth 14, while the opposite end is downwardly curved as at 21.

A spring actuated backstop 22 is mounted 85 to slide across the members 1 and 2, one edge of said backstop sliding against the guide 12 while the opposite edge is adapted to bear against projecting pins or rivets 23. A spiral spring 24 is mounted in the backstop 90 22 and one end of said spring bears against the upper edge of the member 1, while the opposite end bears against a screw threaded plug 25, said plug being adjustable in the backstop to regulate the tension of the 95 spring 24. The lower end of the backstop 22 is inclined, as shown at 26, to engage the ratchet teeth 14, and the outer portion of the part 26 bears upon the curved surface 21 of the pawl 20 to hold the nose 27 of the pawl 100 into engagement with the teeth 14 during one movement of the lever 15. The pawl 20 is engaged frictionally with the member 15, so that when the lever is moved toward the left, as shown in Fig. 2, the nose 27 of the pawl will disconnect from the teeth 14 until the curved member 21 comes in contact with the part 26 of the backstop, at which time the nose 27 will be forced upwardly into engagement with one of the teeth 14. 105

The operation of the stretcher may be briefly described as follows: The clamps are 110

engaged with the wire α at some distance apart, and the wire α is severed between the clamps. By moving the lever 15 toward the right, the member 2 is moved in the same 5 direction through the guides 11 and 12, and the opposite ends of the wire α are brought together and by means of a suitable plier or tool the severed ends are twisted and the slack is taken up. It is to be noted that the 10 members 1 and 2 are disposed at some distance from the wire α , and hence there is plenty of room to operate the pliers for twisting the ends of the wire together.

Various changes may be made in the 15 details of construction without departing from the spirit and scope as defined in the appended claims.

What is claimed is:—

1. A wire stretcher comprising a relative 20 stationary member, a relative movable member having ratchet teeth and being slidably mounted on the relative stationary member, a guide carried by the relative stationary member and engaging the other member, a 25 back stop slidably mounted on the relative stationary member and its lower end coöperating with the teeth of the movable member, and spring means holding the back stop in an adjusted position upon the members.
2. A wire stretcher comprising a relative 30 stationary member, a relative movable member provided with ratchet teeth and slidably mounted on the relative stationary member, guides carried by one of the members and 35 engaging the other member, a back stop

secured to the stationary member and having its lower end curved to conform to the configuration of the teeth of the movable member, a spiral spring seated in the upper end of said back stop, one end of said spiral spring resting on the upper edge of said stationary member, a screw plug on the end of said back stop for engaging the free end of said spiral spring for adjusting the tension of said back stop on the stationary 45 member.

3. A wire stretcher comprising a relative stationary member, a relative movable member provided with ratchet teeth and slidably mounted on the relative stationary member, 50 a guide carried by one of the members and engaging the other member, a back stop slidably mounted on the relative stationary member for coöperating with the teeth of the relative movable member, a lever pivoted to the relative stationary member, a dog carried by the lever, said dog having an upwardly turned end and its opposite end curved downwardly, the curved portion of the dog engaging the back stop when the 55 lever is moved in one direction, such engagement throwing the upwardly curved portion of the dog into engagement with the teeth.

In testimony whereof I affix my signature 65 in presence of two witnesses.

THOMAS M. SNELLING.
